Des. 215,383
Patented Sept. 23, 1969

215,383

DEEP FAT FRYER

Lewis Frank Moore, 711 Evangeline Drive 71106;
Robert L. Dunkelman, 801 Lark Ave. 71105; and
Travis E. Schermerhorn, Jr., 434 Monrovia
71106, all of Shreveport, La.

Filed Mar. 8, 1968, Ser. No. 10,893

Term of patent 14 years

Int. Cl. D7—04

U.S. Cl. D81—10

Fig. 1.

Fig. 2.

*Fig. 3.**Fig. 4.**Fig. 5.*

FIGURE 1 is a rear perspective view of a deep fat fryer with the baskets in a lowered position and the covers closed,

FIGURE 2 is a front perspective view thereof,

FIGURE 3 is a front perspective view with a lid and basket in a raised position,

FIGURE 4 is a front perspective view with one lid in the opened position, and

FIGURE 5 is a front perspective view with both lids raised and the baskets removed therefrom.

We claim:

The ornamental design for a deep fat fryer, as shown and described.
